SIGNALING SWITCH CONSTRUCTION

Christian Miller, Norwalk, Conn., assignor to Edwards & Company, Inc., Norwalk, Conn., a corporation of New York

Application April 22, 1947, Serial No. 743,100

11 Claims. (Cl. 200—16)

1

This invention relates to hospital signalling switch construction, more particularly to a switch construction of the kind to be operated by a bed patient to actuate signals for the call of an attendant or the like.

One of the objects of this invention is to provide a practical and dependable signalling switch construction for the use of bed patients, and one that will reliably and efficiently overcome the various and many structural, functional and other disadvantages of heretofore known signalling switches made available to hospitals and the like for the use of bed patients. Another object is to provide a switch of the above mentioned character which may be dependably secured and held in place, as by attachment to the bed clothes, and thereby also reliably maintained in a position for the intended and desired actuation by the patient. Another object is to provide a switch construction of the above mentioned character by which it will be possible to avoid the inconvenience and damage caused by the use, in present-day equipment, of safety pins in the endeavor to fasten a switch to the bed clothes, and to provide a construction which may be secured in position in such co-acting relationship of the various parts that ease and convenience of manual actuation by the patient are reliably achieved and maintained.

Another object is to provide a bed-side or patient's signalling switch that will be self-locking, to insure the maintenance of the signals once the patient has actuated it, and in which convenient and fool-proof unlocking control means, for actuation by the answering attendant, are provided. Another object is to provide a switch construction of the just-mentioned character with unlocking means so constructed and so functioning as not to be confusing to the patient, and moreover to be substantially inoperable by, though accessible to, the patient.

Another object is to provide a hospital signalling switch of the above mentioned character that will be strong, durable and compact, yet well adapted for connection to, and to handle, multi-conductor cables or cords. Another object is to provide a switch construction of the above mentioned character that will be economical manufacture, capable of ready assembly, and capable also of ease and facility of installation. Another object is in general to provide a hospital signalling switch of improved and more advantageous structure and operation, and other objects will be in part obvious or in part pointed out hereinafter.

2

The invention accordingly consists in the features of construction, combinations of elements, and arrangements of parts as will be exemplified in the structure to be hereinafter described and the scope of the application of which will be indicated in the following claims.

In the accompanying drawing in which is shown a preferred embodiment of my invention:

Figure 1 is a top plan view of the complete hospital signalling switch;

Figure 2 is an end elevation as seen from the right in Figure 1;

Figure 3 is a vertical sectional view as seen along the line 3—3 of Figure 1, certain external parts being shown in elevation;

Figure 4 is a bottom elevation as seen with the bottom wall and certain related parts removed, being substantially a horizontal sectional view as seen along the line 4—4 of Figure 2;

Figure 5 is a horizontal sectional view as seen along the line 5—5 of Figure 2, being also and substantially a sectional view as seen along the line 5—5 of Figure 6;

Figure 6 is a vertical sectional view as seen along the line 6—6 of Figure 1;

Figure 7 is an elevation of a frame part or mounting element;

Figure 8 is an isometric view of a combination frame part; and

Figure 9 is an elevation or plan view of two locking elements.

Similar reference characters refer to similar parts throughout the several views of the drawing.

Referring first to Figures 1, 2 and 3, I preferably provide a casing structure that is of substantial width and length and of relatively low height so that, when resting on the bed clothes or upper part of a bed or hospital patient's equipment, it will have preferably a flatness of shape or form, thus making it less obtrusive in appearance and also contributing to its stability against being tipped over, and as is later pointed out I preferably make provision to give the complete switch structure a very low center of gravity, thus to better insure maintenance of its upright position throughout the varying conditions of practical use. The casing structure comprises preferably a casing 10 having a top wall 11, opposed end walls 12 and 13 and opposed side walls 14 and 15, all preferably merging together in suitable curvatures somewhat as indicated in the drawing, with the end wall 13 preferably of smaller width and height than the opposite end wall 12. These curvatures are preferably such that they do not

present any plane or flat surface of any substantial area in order thereby not to suggest or present any face or wall which might be treated as a bottom wall by which to rest the device on a supporting surface. The side and end walls however terminate in an end peripheral edge 16 which falls preferably substantially in a plane, and co-acting therewith is a bottom plate generally indicated by the reference character 17 and which is shaped to be received within and secured to the casing 10 so as to present an under-face that is substantially in the plane of the edge 16.

Preferably the side and end walls are internally shaped to provide a substantially continuous internal ledge or shoulder 18 against which the bottom plate 17 rests and is secured by any suitable means such as screws 20 which are threaded into suitable enlargements or abutments 21 integrally formed with the shoulder 18, and illustratively three in number, as shown in Figure 4.

The casing 10 is preferably made of any suitable moldable material or so-called "plastic" such as Bakelite or the like, and the configuration shown in the drawing and above described is one that lends itself readily to molding out of such materials. Moreover it is provided with a relatively large hole 22 (Figures 1 and 6) in the top wall 11, illustratively square in shape, and with two relatively small and preferably round holes 24 and 25 in the side walls 14 and 15 respectively, being positioned near the junction with the top wall 11 and preferably so that they and the top hole 22 are substantially aligned transversely of the structure. In molding the casing 10, I also shape and provide it with relatively thick shoulders or abutments that project from the internal face of the top wall 11, as indicated at 26, 27 and 28 (see Figures 4 and 5) which provide suitable plane surfaces which preferably fall in the plane of and are spaced only slightly downwardly from the top wall 11, as viewed in Figure 3, thereby to provide rests or supports against which the arms 30, 31 and 32 of a frame plate 33 respectively engage, to be detachably secured in place as by screws 34 which pass through suitable holes in these arms and are threaded into the shoulders or abutments of the casing wall 11, being preferably threaded directly into the plastic, although they may be threaded into suitable threaded metal inserts molded into these abutments in any usual or known form and manner. Frame plate 33 has assembled to it a switching structure as is later described, thus to form a sub-assembly which, as a unit, may be inserted through the bottom open end of the casing 10 and secured in place as by the screws 34 above mentioned. To this switch structure any suitable number of insulated cable conductors are to be connected and the cable I preferably run into the interior of the casing 10 through one of the walls of the latter, preferably the small end wall 13 in which is formed, during molding, a cut-out 35 (Figures 2 and 4), the cable being simply laid into the cut-out 35 which opens into the lower casing edge 16 and which is thereafter closed off at its otherwise open end by the bottom plate structure 17 (Figure 2) which is secured in place by screws 20 (Figure 4) that are threaded into the molded abutments 21.

The frame plate 33 is in the form of a heavy sheet metal stamping, having an outline and shape as is better shown in Figure 7. Between the arms 31 and 32 the plate 33 is shaped to provide two spaced long extensions 33^a and 33^b and

5 to either side of the arm 30 are provided two similar, and similarly spaced, extensions 33^c and 33^d, each extension being suitably shaped to provide a shoulder S spaced inwardly from its extreme end, thus also leaving narrower end portions E which are later to serve as securing ears or lugs. The points from which these extensions extend from the plate 33 are preferably located equidistantly on a circle, and the plate 33 has, 10 at its center, a round hole 37 whose axis is at the center of that circle, the metal of the plate 33 about the hole 37 being drawn downwardly as at 15 33^e (Figure 6) to form a cylindrical bearing for slidably guiding a switch element 38 which is 20 carried by and preferably integrally formed, as a single metal element, as of brass, with a stem 40 which, above the switch element 38, has a cylindrical part 41 that is dimensioned neatly to slide in the bearing 33^e. The upper end of the stem 40 has secured to it a button 42 preferably of non-conductive material and dimensioned and shaped to be loosely received in the hole 22 of the casing top wall 11. The button 25 42 is thus substantially square in plan (Figure 1), may be made of any suitable plastic, and may be secured to the stem 40 in any suitable way, preferably by providing the latter with a shouldered or lesser-diameter threaded end portion 40^a which is threaded into a threaded hole in the button 42.

30 The extensions 33^a, 33^b, 33^c and 33^d, shown in development in Figure 7, are however bent at right angles to the plate 33 in directions away from the observer viewing Figure 7, and as is 35 better shown in Figures 5 and 6, thus bringing their four shoulders S into a plane parallel to the plate 33 and spaced downwardly therefrom, to receive a member 43 (Figures 6 and 4) which is generally circular and is provided with four 40 holes 43^a, 43^b, 43^c and 43^d through which these extensions are respectively received up to the shoulders S, whence the narrower end portions or ears E of the extensions are bent over to clamp the part 43 securely between the shoulders S and the bent-over ears E. As seen in Figure 6, the part 43 is thus secured in depending relation, but rigidly, to the frame plate 33. If desired, arms 33^a and 33^b can be spaced somewhat more widely apart than 33^c and 33^d to insure that 45 assembly will be made in the correct way.

50 The part 43 is made of any suitable non-metallic material, preferably a molded and cured resin or other plastic. It has a central hole 44 in which is slidably received the lower end of the stem 40 about which is a helical spring 45 which reacts between the part 43 and the switch element 38 to bias the latter and the stem always upwardly (Figure 6), the stem structure and spring, with the button 42 removed, being first 55 assembled to the hole 44 in the part 43 before the part 43 and the frame plate 33 are secured together by the plate extensions as above described. The hole 44 thus forms a dependable guide for the lower end of the stem 40, during 60 the up and down movements, later described, of which these parts partake.

65 Let it be assumed that the switch structure is to control more than one electrical circuit, usually and illustratively in hospital bedside signaling systems, being five in number; in the latter case I prefer to provide the switch structure with six conductor-connecting elements to which the 70 six conductors of the cable may be electrically and mechanically connected, one of them being a conductor that is the "common" conductor of all

five circuits. These connector elements, conveniently in the form of screws 46 (Figure 4) are preferably exposed on the under face of the part 43, preferably equiangularly spaced about the circular area of that face, which is also preferably recessed as at 47, one recess for each binding screw, to retain the wire.

Each binding screw is threaded into a headed or shouldered metal bushing 48 (Figure 6) which is secured in any suitable way in a hole in the part 43, there being one hole opening into each recess 47 for that purpose, and the upper shouldered end of the bushing 48 serves to clamp in position the horizontal shank 50 of a spring sheet metal contact element which is bent into a V-shape, as is indicated in Figure 6, to provide a springy and yieldable and vertically elongated contact 51 that is positioned in the path of downward movement of the bridging or switching element 38 above described. The shank part 50 is provided with a suitable hole through which the bushing 48 passes and the bushing is preferably knurled or roughed up on its external surface to make strong interlocking engagement with the material of the part 43 into the hole in which the bushing may be press-fitted.

As is better shown in Figure 6, the part 43 can be of relatively substantial thickness, and above the hole 44, and co-axially with the latter, it has a recess 52 for accommodating the spring 45 which is about the lower portion of the stem 40, and grouped in a circle about its axis, the part 43 is provided with a series of recesses or wells 53, one for each of the six V-shaped contact elements 51, each well 53 being of the same width as the sheet metal of the contact element 51 so that it cannot partake of rotary displacement about the axis of the bushing 48 which extends through the hole in the shank 50. Thereby also the contact elements 51 which project upwardly beyond the upper face of the part 43 are grouped in a circle about the axis of the switch stem 40 and are neatly positioned in the path of downward movement of the switch member 38. If the spring contact arms 51 are all of the same length in their upward projection beyond the face of part 43, downward movement (Figure 6) of the stem 40, when the button 42 is depressed, brings the switch member 38 into wiping and self-cleaning engagement with all of the elements 51 and all of the circuits are closed, the switch element 38 camming the members 51 radially outwardly against their spring action. If desired, however, and as later described, one or more of the contact elements 51, other than that to which the "common" is connected, may be of shorter length than the others so that they are not engaged and their circuits are not closed excepting when the stem 40 and its switch element 38 are given a slight additional depression. For purposes of illustration I have shown in Figure 6 one such other contact element, indicated at 51^a other than the "common," which is shorter than the rest of the elements 51.

I next provide for locking the stem 40 in depressed position against the spring 45, and preferably for locking it at a point in its downward movement that falls short of its maximum intended depression. Such locking means I preferably arrange to co-act with the enlarged stem part 41 and it preferably comprises two locking elements 55 and 56 shown in plan in Figure 9. These are constructed so that they may be easily formed by stamping out of sheet metal and they comprise somewhat elongated shanks 55^a and

56^a which are at their ends bent at right angles as at 55^b and 56^b (Figure 9, and see also Figure 6). Each has a widened rectangular part 55^c and 56^c which at one edge or side are cut out as at 55^d and 56^d, at least one edge of the cut-out, as at 55^e and 56^e, being of a radius about equal to the radius of curvature of cylindrical stem enlargement 41, and each being of preferably less than 180° in arcuate extent. The mouth of each of these cut-outs is equal to or greater than the diameter of the stem part 41.

These two locking members 55, 56 rest upon the face of the frame plate 33, with the portions 55^c and 56^c overlying each other, their respective large areas insuring ample bearing surfaces for relative sliding movement therebetween, as well as between them and the upper face of the frame plate 33 and the under face of an auxiliary frame part generally indicated by the reference character 57 and better shown in perspective in Figure 8.

The frame part 57 is a sheet metal stamping and has a central portion 57^a from which depend side pieces 57^b and 57^c which are spaced apart by a distance equal to the equal widths of the overlying portions 55^c and 56^c of the locking members 55 and 56, and they are of a height which is a little greater than the thickness of these overlying parts.

30 The frame part 57 has also opposite end portions 57^f and 57^g which have opposed and depending side parts which are parallel to the side parts 57^b and 57^c and spaced from each other by about the width of the shanks 55^a and 56^a of the locking members. The latter, in their shanks, have cut-out and bent downwardly, lugs 55^h and 56^h which are of a length to pass through transversely elongated slots 33^h and 33^k (Figure 7) in the frame plate 33, when the two locking members are, in assembly, rested upon the frame plate 33 with the parts 55^c and 56^c interlocking with each other. As shown in Figure 8, the auxiliary frame part is provided with a suitable number of lugs L, preferably one for each side piece, and the frame plate 33 is provided with correspondingly dimensioned and spaced holes H into which the lugs L are entered as the frame part 57 is brought over the superimposed locking members 55 and 56, whence the lugs L may be expanded or headed over on the under side of the frame plate 33 to complete the assembly of these two parts.

The overlying locking members 55 and 56 are thus neatly housed and guided for relative transverse movement to an extent permitted by the lengths of the slots 33^h and 33^k through which the lugs 55^h and 56^h of the two locking members project below the inner face of the frame plate 33. There these lugs are engaged by the two arms 58^a and 58^b of a helical spring 58 through which extends a headed stud or pin 60 (Figure 7) from the under side of the plate 33 to hold the spring assembled to it.

These spring arms, acting upon these lugs, 65 yieldably hold the two locking devices in their position of maximum displacement away from each other, positions which bring the arcuate edges 55^e and 56^e closest to each other, thus to restrict the closed hole which the overlying parts 70 55^c and 56^c form in their overlying relation, the one closing off the side mouth of the other, and if the upper portion of stem 40 (Figure 6) is in the path of this relative movement between the locking parts, the edges 55^e and 56^e can engage 75 that stem 40, and upward movement of the stem,

under the urge of the spring 45, is then blocked by the shoulder formed by the stem enlargement 41 which is brought into engagement with the under faces of the two interlocking parts 55^c and 56^c. In that position of the parts, the button 42 having been depressed to bring the stem enlargement 41 below the overlying locking parts, the switch member 38 is in engagement with all of the longer contact elements 51, one of which is the "common," but is not in engagement with the shortest one or more of the remaining contact elements, such as the element 51^a. Accordingly all of the signal circuits excepting that to which the shortest contact or contacts (part 51^a, illustratively) is connected, are energized and their corresponding signals actuated. A subsequent additional manual depression of the button 42 brings the switch element 38 into contact with the element 51^a for as long a time as this additional depression is maintained, and the signal of that circuit is correspondingly actuated.

If the two locking members 55 and 56 are both moved inwardly toward the axis of the stem 40 and against the action of the spring 60, the arcuate edges 55^e and 56^e are moved away from each other and as soon as they form a hole large enough for the stem enlargement 41 to enter it, the spring 45 urges the stem upwardly, the enlargement 41 enters that enlarged hole, and subsequent action of the spring arms 58^a and 58^b is ineffective to move the locking elements toward each other, for such movement is now blocked by the presence of the enlargement 41 in the paths of movement of the arcuate edges 55^e and 56^e. The annular bearing flange 33^e (Figure 6) serves as a stop by which the upward movement of the stem is limited when the laterally projecting switch element 38 engages the flange 33^e. At the center of the frame part 57 is a hole 57^k through which the upper part of the stem 40 passes co-axially, and preferably the hole can be large enough to accommodate stem enlargement 41 in its upward movement into its uppermost position, for in that way it is possible to make certain that the stem enlargement 41 bridges the gap or space between the plate 33 and the plate portion 57^a to form an effective stop against which the spring arms 58^a and 58^b press the edge portions 55^e and 56^e of the locking elements and more particularly to form an effective stop against relative movement of the locking elements toward each other should manual pressure be applied to the bent end portions 55^b and 56^b. The stem enlargement 41, when in this uppermost position, thus blocks the locking elements against relative inward movement, the edges 55^k and 56^k (Figure 9) bearing against diametrically opposite portions of the stem enlargement 41.

The build-up frame and switch structure carried by it may thus be made up and assembled as a sub-unit or sub-assembly and is ready to be assembled to the casing 10. Before inserting it into casing 10, two flanged or shouldered buttons 61 and 62 (see Figure 6) are inserted, from the inside, into the round holes 24 and 25 respectively that are positioned in the casing side walls 14 and 15 at such respective points that, when the frame arms 30, 31 and 32 (Figures 4 and 5) rest against the shoulders 26, 27 and 28 respectively and the screws 34 are put in place, the inner flanged or headed ends of the buttons 61 and 62 are respectively juxtaposed to the bent ends 56^b and 55^b of the locking members 56 and 55, and the button 42 is projected into the hole 22 in the casing top wall 11.

The parts are so proportioned that, with the locking members 55 and 56 held in outermost position, a position which they occupy when the stem enlargement 41 is in uppermost position as above described, the spacing between the bent ends 56^b and 55^b from the respective casing side walls is materially greater than the axial length of the heads or flanges of the buttons but not greater than the axial length of the button shanks, and hence the latter cannot fall out of place. As indicated in the drawing, the buttons are relatively small and inconspicuous compared to the large and upwardly projecting top button 42. Accordingly the patient, to whom the signalling switch structure is allocated, actuates the button 42 in the top wall of the casing by depressing it against the action of spring 45.

When the button 42 is depressed sufficiently to bring the upper shoulder end of the stem part 41 below the upper face of the frame plate 33 (Figure 6), the switching element 38 engages all of the longer contacts 51 and both locking elements 55 and 56 are snapped outwardly away from each other under the action of the spring arms 58^a and 58^b as above described, locking the switch member 38 in the above described position of contact with the longer contacts 51. The bent ends 56^b and 55^b of the locking parts move outwardly (Figure 6) by respective distances just about equal to the difference in the radii of the parts 41 and 40, the arcuate edge portions 55^e and 56^e of the locking members engaging the upper stem part 40 to limit the outward movement of the locking parts. The latter movements, by the engagement of the bent parts 55^b and 56^b with the buttons 62 and 61, project the latter outwardly and laterally of the casing side walls 14 and 15, the spacing between the bent ends from the respective casing side walls being just about sufficient to accommodate the heads or flanges of the buttons which are thereafter held in projected positions through the action of the spring arms 58^a and 58^b upon the two locking parts.

The signal circuits closed by the now locked engagement of switch member 38 with the longer contacts 51 remain actuated or energized, but should the patient desire to actuate, usually repeatedly, an additional signalling device, usually audible such as a buzzer, the patient need only depress the button 42 to the additional extent above described, thus closing an additional signalling circuit at the shorter contact spring 51^a (Figure 6). Such additional actuation cannot and does not affect the locking action above described so that cessation of such additional or supplemental actuation of the button 42 does not interfere with the continued maintenance of the closure of the other signalling circuits at the longer contact springs 51. When the attendant responds to the call, the small side buttons 61 and 62 stand projected laterally from the side walls of the casing and the attendant presses both of them inwardly to cause the locking parts to release the stem part 41 which, under the action of spring 45, moves upwardly with its related parts, interrupting all of the circuits and now projecting the top button 42 upwardly beyond the casing; the bent ends 55^b and 56^b of the locking members move inwardly as above described, making ineffectual any possible manipulation of either or both of the buttons 61 and 62 so that thereafter, should the patient again call, the only part available for effective signalling actuation is the button 42.

The bottom plate 17 (Figures 2, 3 and 6) is

preferably of composite construction, and preferably comprises a sheet 65 of a dense or heavy metal such as lead or lead-alloy, being of sufficient thickness and expanse and hence of weight relative to the remaining parts of the assembled construction as to very materially lower the center of gravity, as viewed in Figures 3 and 6 and bring it into or as near as possible to a horizontal plane in or adjacent the lower end of the casing 10, and preferably also it is so distributed that the center of gravity falls in or close to the vertical axis of the button 42. The structure is thus given a great inherent stability against tipping over, thus to coact to maintain it upright when its bottom face rests upon an irregular or slanting portion of the bed, bed clothes or other parts. Preferably the under face of the lead plate 65 has secured to it, as by an adhesive, a sheet 66 of friction material such as relatively soft rubber, preferably rubber presenting an external irregular or roughened surface somewhat like sponge rubber, thus giving it good resistance to sliding out of desired location, particularly when it is positioned upon a part that slants or inclines.

It has been found in past practice that it is frequently desirable to secure the signalling switch construction to the bed clothes and heretofore resort has been had to the use of pins and safety pins by which the flexible cable or cord extending from the switch structure is pinned to the sheets, blankets or the like. Such practices have been found to cause considerable damage to the sheeting, but according to my invention the above described features of low center of gravity, coupled with relatively large flat expanse of bottom surface of the structure, and also the non-slip feature of such under surface, can in large measure serve to avoid the need of using such damage-causing devices as safety pins. However circumstances of use may arise where a positive fastening of the signalling device is desired and in such case I may provide in the bottom plate structure 17 a gripping device by which a suitable fold of the sheeting, blanket or the like may be dependably and detachably engaged, and that device I preferably arrange to be accommodated within or under that portion of the casing that narrows down both in height and width, such as the right-hand portion in Figures 1 and 3 which terminates in the end wall 13 where the flexible cable enters through the cutout or slot 35 (Figures 1, 2 and 3). As is better shown in Figure 3, I may thus utilize certain of the internal space to the right of the switching mechanism, more particularly to the right of the solid dielectric member 43.

The gripping device preferably comprises a somewhat elongated plate part 67 which inclines downwardly from an internal upper point closely adjacent the part 43 to a point at the inside face of the end wall 13 and closely adjacent the bottom edge thereof, and in cross-section it is preferably U-shaped, having tapered side walls 68 and 69 (Figures 3 and 4) which are suitably apertured to support a pin 71 by which a clamping lever 72, preferably of sheet metal, is pivoted, the clamping lever having suitable side flanges or ears 73 and 74 through which the pin 71 extends. A spring 75 extends about the pin 71 and has its end arms extending respectively against the plate part 67 and against the lever part 72 to strongly bias the lever 72 in counterclockwise direction as viewed in Figure 3. At its right-hand end the lever 72 is suitably shaped,

as by appropriately shaping the flanges 73 and 74, to provide suitable teeth 77 which, by the spring 75, are pressed upwardly (Figure 3) against the lowermost portion of the inclined plate part 67 which, in any suitable manner, as by appropriately stamping or shaping the sheet metal, may be provided with companion teeth 78 (Figure 3) to coact with the teeth 77.

In normal position and with no material or other part interposed between the companion gripping jaws or their teeth, the spring 75 holds the parts in about the position shown in Figure 3 in which the flat plate-like portion of the lever 72 falls in a plane parallel to the plane of the bottom edge of the casing 10 or in the general horizontal plane of the bottom plate 17, thus to present and maintain a substantial closure of what is in effect a tapered upwardly extending recess projecting into the interior of the casing 10. The bottom plate structure thus presents no such irregularities or projecting parts as would catch on the bed clothes or the like or as would mar a finished furniture surface if the device were rested thereon, or as might cause injury to the fingers or hands in handling the device, and this is of advantage where the device is used as above described, namely, without having to place reliance upon the gripping or clamping device.

However, it will be noted that the handle portion of the lever 72, namely, that portion to the left of the pin 71 in Figure 3, remains juxtaposed to and spaced from that portion of the inclined plate part 67 that is of greatest projection inwardly into the interior space of the casing 10, and hence when it is desired to bring the clamping device into action, a suitable finger pressure is applied to the lever 72, in an upward direction in Figure 3, and the lever 72 responds only when that pressure is applied to the left of the pin 71, thus making the device simple and fool-proof to manipulate. When lever 72 is so depressed to swing it in clockwise direction, its right-hand end with the teeth 77 is projected well below the plane of the bottom edge of the casing 10 and below the bottom edge of the narrow end wall 13 which thus coacts to guide a suitable fold of the material such as a sheet or a blanket, into the opened gripping device which may then be released to let the strong spring 75 clamp and grip the material between the companion gripping jaws or teeth 77 and 78, the gripping action being aided by the distortion of the fold of material into a substantially U-shaped cross-section as the jaw end of the lever 72 presses it upwardly in Figure 3 into the shallow end of the tapered recess, the lever structure 72, or its jaw end, being preferably made of appropriately lesser width than the spacing between the parallel side wall parts 68 and 69 to permit this action to take place, particularly with respect to thinner cloth material such as sheeting. When thus clamped to the bed clothes or the like, the above described low center of gravity of the complete switching structure contributes to the stability of the device against being easily turned over and thus coacts to lessen the strain and burden to which the clamping device itself may be subjected in having to hold the switch structure in position against the varying conditions inherent in the use of the device.

The various wall parts that form the recess of varying depth in which the clamping lever 72 functions may be easily formed, as by stamping, in the sheet metal of which the bottom plate 17 may be formed or constructed, and if it is desired

to utilize a sheet metal such as sheet iron, the wall parts may be so drawn or stamped out of such material to form also a plate 76 (Figures 3 and 6) whose periphery is shaped suitably to rest against the ledge 16 (Figure 4) that extends peripherally in the bottom edges of the side walls, and to the under side of such a bottom plate element 76, the plate part 65 of lead or other dense and heavy metal, may adjoin or be secured in any suitable manner, to form a unitary bottom plate structure, with the friction material 66 in turn secured to the under-face of the lead plate part 65, thus to make up the bottom plate 17 of which the just described features of construction and assembly are illustrative. Where the bottom plate 17 is built up in this manner, the lead plate part 65 and the friction material 66 are cut away throughout the area of the tapered depression or recess outlined by the side wall parts 68 and 69 (Figure 4) and the end wall 70 adjoining them at one end.

It will thus be seen that there has been provided in this invention a signalling switch construction in which the several objects above set forth, together with many thoroughly practical advantages, are successfully achieved. The construction is compact, neat in appearance, and of fool-proof construction and action. It can be easily assembled and can be installed with convenience and facility. In this latter connection it might be noted that, as is better seen in Figure 3, the downwardly and outwardly inclined wall 67, at its lower-most end, closes off the slot 35 to coact with the walls of the latter in neatly holding in place that portion of the flexible and usually rubber covered cable that enters the closed casing, and desirably the parts are so proportioned that a suitable clamping action on the cable or on a rubber bushing surrounding it can take place, and for that purpose appropriate portions of the end wall 13 may be molded, throughout the upper arcuate regions of the slot 35, to provide a relatively large expanse of arcuate or curved surface 35^a (Figure 3) against which the cable can be clamped or pressed by the portion 67 of the bottom plate, the two screws 20 (Figure 4), one on each side of the resultant clamping structure, insuring secure and strong clamping action of these parts. Moreover the inclined wall portion 67 forms a guide and a rest for the inner end of the cable and its sheath, from which the individual insulated conductors illustratively six in number, may be fanned out for individual connection to and by the binding screws 46 (Figure 4), some of them passing conveniently to the left of wall 68 and the dielectric switch base 43 and others passing to the right of wall 68 and the base 43, as they pass on their way to the more remote and laterally distributed binding screws of which some are to the left of the vertical axis in Figure 4 and others are to the right. These conductors are easily so fanned out and so connected with the bottom plate 17 removed, the cable simply resting against the arcuate walls of the slot 35, and when the bottom plate 17 is put in place and secured by the screws 20, the anchorage or clamping of the cable as above described is completed, and any disturbance of the fanned-out relationship of the conductors, under any pulls exerted upon the cable, can be thereby lessened or avoided.

As many possible embodiments may be made of the above invention and as many changes might be made in the embodiment above set forth, it is to be understood that all matter hereinbefore

set forth or shown in the accompanying drawing is to be interpreted as illustrative and not in a limiting sense.

I claim:

5. A hospital-bed type of switch comprising a casing having opposed side walls with apertures therein and having a top wall with an aperture, a spring-biased manually-depressible actuator projectable externally of the casing and by way of said aperture, manual actuators slidably carried by said opposed side walls and in said apertures, switching mechanism within said casing and operable in one direction in response to depression of said actuator and having locking means operating in response to such depression to hold said switching mechanism in operated position, said locking means having two operating members to effect release thereof and positioned in respective juxtaposition to said manual actuators in the opposed side walls of said casing for actuation thereby from the exterior of said casing.

20 25 2. A switch as claimed in claim 1 in which said manual actuators are in the form of headed elements inserted into said apertures from the inside of said casing whereby said two operating members hold them against inward movement out of their respective apertures.

30 35 3. A switch as claimed in claim 1 in which said two operating members are provided with means operating in response to depression of said actuator to project them outwardly away from each other and thereby effect outward movement of said manual operators on opposed sides of the casing to position them for manual actuation when release of said locking means is to be effected.

40 45 4. A switch construction comprising a casing open at its bottom and having an apertured top wall and opposed apertured side walls, a frame insertable into said casing and having a portion substantially parallel to the top wall and provided with transverse slideways having therein two co-acting locking means for sliding toward or away from each other, said locking means having manual actuators respectively exposed through the apertures in said opposed side walls, said frame carrying switching mechanism having an operator movable crosswise of the paths of sliding movement of said two locking means to be locking engaged by the latter upon movement in one direction, said operator having a manual actuator exposed through an aperture in said top wall for manual actuation to move said operator in said one direction to actuate said switch mechanism and to be engaged in locking relation by said two locking means to hold the switch mechanism in actuated condition.

50 55 5. A switch as claimed in claim 4 in which said switching mechanism comprises a carrier insulatingly supporting a plurality of switch contacts grouped about the axis of said operator and providing a sliding bearing for the latter, said operator having conductive means movable in response thereto to engage said switch contacts.

60 65 6. A switch as claimed in claim 4 in which said switching mechanism comprises a carrier insulatingly supporting a plurality of switch contacts grouped about the axis of said operator and providing a sliding bearing for the latter, said operator having conductive means movable in response thereto to engage said switch contacts, one of said switch contacts being of different length than the rest and thereby requiring an additional movement of said operator beyond the locking position to effect engagement therewith.

70 75 7. A switch construction comprising a casing

structure having therein a sub-assembly comprising a frame carrying switching mechanism having an operator movable to actuate said switching mechanism in one direction and locking means movable transversely of the path of movement of said operator and to lock the latter in response to movement thereof in said one direction, said locking means comprising two substantially hook-shaped locking members engaging said operator from opposite sides thereof and having means biasing them into engagement therewith, said operator having a stepped portion into which said hook-shaped locking members enter, said locking members terminating adjacent opposed side wall portions of the casing, and two actuators carried by the latter for operating said locking members in opposite directions from the exterior of the casing.

8. A switch construction comprising a casing structure having therein a sub-assembly comprising a frame carrying switching mechanism having an operator movable to actuate said switching mechanism in one direction and locking means movable transversely of the path of movement of said operator and to lock the latter in response to movement thereof in said one direction, said locking means comprising two substantially hook-shaped locking members engaging said operator from opposite sides thereof and having means biasing them into engagement therewith, said operator having a stepped portion into which said hook-shaped locking members enter, said locking members terminating adjacent opposed side wall portions of the casing, and two opposed side wall portions having externally operable actuators to which said locking members are respectively interrelated upon assembly of said sub-assembly to said casing to effect operation thereof from the exterior of the casing.

9. A hospital-bed type of signalling switch comprising a casing structure with a bottom and being of substantial width and length and of relatively low height and thereby having a high factor of stability, said casing structure having a top wall with an aperture from which is projectable an actuator that is manually depressible in a direction toward the bottom, thereby to lessen disturbance, by actuation, of the stability factor of the device, said casing containing

switching mechanism operable in one direction in response to depression of said actuator with locking means operating in response to such operation to hold said switching mechanism in operated position, said locking means comprising a plurality of locking members all of which effect locking or holding action upon said switching mechanism, said casing having laterally projecting therefrom a plurality of inwardly movable release actuators, one for each locking member, whereby release of said switch mechanism from operated position can be effected only by inward pressing of all of said release actuators.

10. A hospital-bed type of signalling switch comprising a casing of substantial width and length and of relatively low height and thereby having a high factor of stability and having switching mechanism therein with manual actuator exposed from a wall of said casing and movable for signalling actuation of said switching mechanism in a direction having little disturbing effect upon the factor of stability, with locking means responsive to said signalling actuation for holding said mechanism in actuated condition, and a plurality of manual actuators movably carried by said casing for controlling unlocking actuation of said locking means whereby all of said plurality of actuators must be actuated to effect release of the switching mechanism from signalling position.

11. A hospital switch as claimed in claim 10 provided with means responsive to actuation of the switching mechanism in signalling direction for positively moving said plurality of manual actuators to respective positions of projection from said casing and thereby condition them for manual actuation in lock-releasing direction.

CHRISTIAN MILLER.
